[57] **ABSTRACT**

A hopper is provided which is filled with a stack of paper bags or other material to be baled. The bags are transferred to a compression area where the stack is compressed. Straps are drawn about the stack and secured. The strapped bale is then discharged.

STRAPPING APPARATUS

This invention relates to an improvement in baling apparatus and deals particularly with a device designed for securing objects such as paper bags in tightly baled condition.

BACKGROUND OF THE INVENTION

Paper bags such as those used in supermarkets and the like are usually packaged in bundles each containing a predetermined number of bags, such as 500 bags for example. A stack of 500 bags is placed between a pair of compression plates which are supported in cantilever style, and the compression plates are moved together to somewhat reduce the size of the stack. In view of the fact that the bottom portions of the flat bags are thicker than the remainder thereof the bags are usually assembled in groups of perhaps 25 bags, and the position of the ends of the bag is alternated so that the stack may be of generally uniform thickness at opposite ends. After the bags have been compressed between the compression plates, a sheet of wrapping paper is applied around the stack of bags and the compression plates, and the ends of the wrapping sheet are taped together to form a sleeve. The bags are then forced from between the compression plates and the stack of bags expands to fill the wrapping sleeve. The wrapping sleeve is often somewhat longer than the stack of bags so that the ends of the sleeve may be folded against the ends of the stack. The sleeve may be either taped or tied in this wrapped condition.

While the stack of bags may be slightly compressed together at the completion of the wrapping operation, usually the degree of any such compression is very small. Obviously, as the wrapping paper is applied both about the stack of bags and the compression plates, the stack may be expanded at least to the volume previously occupied by the stack and the compression plates. Furthermore, in view of the fact that the ends of the wrapping strip are merely taped together, the wrapper would rupture if the degree of compression was very great. In addition, as the amount of compression is increased, the difficulty involved in forcing the stack of bags from between the compression plates is similarly increased. As a result, the packages of bags produced in the normal manner is under no more than slight compression at the most.

While paper bags have been successfully packaged in this way for many years, there are certain disadvantages which have always been present. There is substantially a fixed time for compressing the stack of bags, applying the wrapper around the stack, taping the wrapper to form a sleeve, and ejecting the stack of bags and wrapper. The bags are formed by the bag machine at a relatively high rate of speed. The time required to wrap the bags makes it necessary to package a minimum of perhaps 500 bags in a bundle. If a lesser number of bags were packaged in the bundle, it would be necessary either to reduce the speed of the bag making machine, or else to provide two bag compressing and wrapping stations in place of one, thus doubling the cost of this operation. As a result, the bundles are large and awkward to handle making it difficult for women employees of the supermarket or similar store to handle the bags. Furthermore, the bundles of bags are bulky enough so that a full freight car of bags will weigh far less than the permissible maximum, thus materially increasing the cost of shipping the bags.

SUMMARY OF THE INVENTION

It has been found that if bags are bundled by use of a suitable machine, the bags may be subjected to high compression and tapes such as ribbons of plastic material or the like may be applied to the stack of bags while under compression, much of the compression of the bundle may be retained. By suitably designing the equipment, the bags may be bundled in units containing perhaps 250 bags and the space required per thousand bags may be reduced as much as 40 percent. The resulting bundles are thus relatively small and can readily be handled by the female help of a supermarket or the like. Furthermore, the number of bags shipped in a freight car may be correspondingly increased, resulting in a very material reduction in the shipping costs.

An object of the present invention resides in the provision of a baling apparatus designed to receive and accumulate a stack of bags in superimposed relation.

20 When the desired number of bags is accumulated, the stack is pre-compressed and delivered to a compression section in which the bags are greatly compressed. While held in a compressed condition, straps formed of suitable material are wound about the bundle, and the straps are connected encircling the bundle. The compression is then released, leaving the strapped stack of bags in a highly compressed state. The strapped bundle is ejected from the apparatus, and a new cycle is started.

30 A feature of the present invention resides in the provision of novel means of applying the straps about the bundle or stack. The frame of the compression unit is provided with a track which extends entirely about the bundle when the bundle is completely compressed.

35 Chains are driven into these tracks, the free ends of the chains following the tracks completely about the bundle. Strap engaging means are provided on the free ends of the chains which engage the ends of the straps being fed from supply reels or spools. The direction of

40 movement of the chains is then reversed, drawing the straps completely about the bundle and into overlapping relation with another portion of the strap. The overlapping portions of the tape are secured together and the tape is cut off adjoining the connection. As soon as the straps have been secured in bundle encircling position, the compression is released, and the bundle may be ejected.

45 A further feature of the invention resides in the provision of a construction in which the chain tracks are formed in relatively movable portions of the compression unit. In other words, when the compression plunger is retracted, the tracks are discontinuous. The tracks are only continuous when the compression plunger reaches fully compressed position.

50 A further feature of the present invention resides in the provision of a novel device for forming and applying clips to the overlapping portions of the tape. In preferred form, the clips are supplied in the form of a continuous strip of metal which is preferably provided

55 with opposed notches in opposite edges, the notches defining the ends of the finished clip. The strip of metal is bent into channel shaped form to receive the overlapped ends of the tape, the strip is cut off between the notches of a pair to separate the clip from the remainder of the strip, and the sides of the channel shaped clip are folded to enclose the overlapped ends of the tape. In folding the sides of the clips over the

tape, the clip is preferably bent into corrugated form to prevent the ends of the strap from becoming disengaged.

A further feature of the present invention resides in the provision of an apparatus of the type described including a hopper for receiving the stack of bags and which, after receiving the bags, is tilted so that the stack of bags rests against the wall of the hopper. While in tilted relation, a transfer carriage which straddles the hopper is moved laterally to transfer the bags from the hopper into the compression section of the apparatus. The carriage remains in this position during the compressing and strapping operations. At the completion of these operations, the carriage returns to its starting position, carrying the compressed bundle to a discharge position during this return movement.

BRIEF DESCRIPTION OF THE DRAWINGS

FIG. 1 is a diagrammatic view of a bag baling apparatus showing the input and the stacking apparatus.

FIG. 2 is a diagrammatic view of the bag baling apparatus showing the manner in which a stack of bags is delivered to a hopper.

FIG. 3 is a diagrammatic view of the bag hopper in tilted position.

FIG. 4 is a diagrammatic view showing the transfer of the stack of bags into compression position.

FIG. 5 is a diagrammatic view of the stack of bags in compressed position.

FIG. 6 is a diagrammatic view of the compressed stack of bags being encircled by strap engaging chains.

FIG. 7 is a diagrammatic view of the compressed stack of bags showing the manner in which the straps are drawn about the stack.

FIG. 8 shows the strapped bale of bags after the compression is released.

FIG. 9 is a diagrammatic view of the return transfer of the baled stack of bags.

FIG. 10 is a diagrammatic view showing the discharge of the baled bags.

FIG. 11 is a diagrammatic front elevational view of the hopper portion of the apparatus.

FIG. 12 is a side elevational view of the loading side or left hand side of the apparatus.

FIG. 12A is a diagrammatic view of the transfer carriage frame.

FIG. 13 is a diagrammatic view of a modified form of hopper.

FIG. 13A is a perspective view of the hopper alone.

FIG. 14 is a diagrammatic top view of the frame showing the transfer mechanism.

FIG. 15 is a diagrammatic sectional view on the line 15—15 of FIG. 12.

FIG. 16 is a side elevational view of the compression side, or right side of the apparatus.

FIG. 16A is a sectional view through the compression plate.

FIG. 17 is a diagrammatic view of the chain feed apparatus.

FIG. 18 is a diagrammatic sectional view through a portion of the compression unit showing the tape shearing apparatus.

FIG. 19 is a diagrammatic sectional view of the clip shearing apparatus.

FIG. 20 is a diagrammatic view of the crimping device for securing the clips to the strap ends.

FIG. 21 is a diagrammatic view of the strap release mechanism.

FIG. 22 is a diagrammatic sectional view through the compression unit showing the chain tracks therein.

FIG. 22A is a diagrammatic sectional view on the same plane as FIG. 22 but with the chains retracted and the compression plate in non-compressing position.

FIG. 23 is a sectional view through a portion of the track, the position of the section being indicated by the line 23—23 of FIG. 22.

FIG. 24 is a sectional detail of the chain lock release plunger, the position of the section being indicated by the line 24—24 of FIG. 22.

FIG. 25 is a sectional view through the chain lock, the position of the section being indicated by the line 25—25 of FIG. 24.

FIG. 26 is a view similar to FIG. 22, showing the manner in which the chains draw the straps about the stack.

FIG. 27 is a detail section on the line 27—27 of FIG. 26.

FIG. 28 is a diagrammatic perspective view of one set of interengaging prongs forming the track at the junction between the pressure plates and the remainder of the track.

FIG. 29 is a diagrammatic perspective view of the other set of interengaging prongs cooperable with those of FIG. 28.

FIG. 30 is a view similar to FIGS. 22 and 26 showing the chains fully retracted and the crimper advanced to seal the strap ends together.

FIG. 31 is a diagrammatic view of the strap advance mechanism.

FIG. 32 is a sectional view through a portion of the strap advance mechanism, the position of the section being indicated by the line 32—32 of FIG. 31.

FIG. 33 is a perspective view of the chain end and strap clamp mounted thereon.

FIG. 34 is a longitudinal sectional view through the strap clamp on the chain end.

FIG. 35 is an enlarged diagrammatic view of the strap cutting apparatus.

FIG. 36 is a diagrammatic view of the clip feedings, forming and advancing mechanism.

FIG. 36A is a horizontal sectional view looking upwardly at the under surface of the upper clip forming section, the position of the section being indicated by the line 36A—36A of FIG. 36.

FIG. 36B is a sectional view of the same plane as FIG. 36A, looking downwardly at the upper surface of the lower clip forming section.

FIG. 36C is a vertical sectional view through the clip forming unit, the position of the section being indicated by the line 36C—36C of the drawings.

FIG. 36D is a vertical sectional view, the position of the section being indicated by the line 36D—36D of FIG. 36.

FIG. 36E is a vertical sectional view through the clip forming mechanism on the line 36E—36E of FIG. 36.

FIG. 37 is a perspective view of one end of the clip forming mechanism showing the feed mechanism.

FIG. 37A is a diagrammatic perspective view of the clip forming strip.

FIG. 37B is a diagrammatic perspective view of the strip when partially formed.

FIG. 37C is a diagrammatic perspective view of a clip severed from the clip forming strip.

FIG. 37D is a diagrammatic perspective view of the crimped clip.

FIG. 38 is a perspective detail of the clip forming strip feed device.

FIG. 39 is a diagrammatic elevational view of the clip strip feed device near one extreme position.

FIG. 40 shows the position of the clip feed element in the position shown in FIG. 39.

FIG. 41 is a view similar to FIG. 39 showing the strip feed in an intermediate position.

FIG. 42 is a view similar to FIG. 40 showing the clip feed element in the position corresponding to FIG. 41.

FIG. 43 is a view similar to FIG. 39, showing the clip strip feed in its other extreme position.

FIG. 44 is a view similar to FIGS. 40 and 42, showing the clip feed element in the relation corresponding to FIG. 43.

FIG. 45 is a vertical sectional view through the clip advance carriage.

FIG. 45A is a detail view of the clip ejector.

FIG. 46 is an end view of the clip advance carriage.

FIG. 47 is a sectional view through the lower portion of the carriage on the line 47—47 of FIG. 45.

FIG. 48 is a diagrammatic sectional view through the clip advancing carriage and showing the relation between the carriage and the crimping unit as the clip is ejected.

FIG. 49 is an enlarged diagrammatic view of the crimping unit and its location relative to the straps.

FIG. 50 is an enlarged diagrammatic view of the crimpler element showing the strap gathering jaw.

FIG. 51 is a view similar to FIG. 50 showing the strap gathering jaw in its other extreme position.

FIG. 52 is an enlarged diagrammatic view showing the relationship between two sets of crimping jaws in open position.

FIG. 53 is an enlarged diagrammatic view showing the position of one set of crimping jaws in clip crimping position.

FIG. 53A is a view similar to FIG. 53 and showing the crimping jaws in partially closed position.

FIG. 54 is a diagrammatic view showing the position of the other set of jaws and anvils when closed upon a clip.

FIG. 55 is an enlarged side elevational view of the crimping head.

FIG. 56 is a view similar to FIG. 55 with the jaws in crimping position.

FIG. 57 is a sectional view through the crimpler head, the position being indicated by the line 57—57 of FIG. 59.

FIG. 58 is an enlarged sectional view on the line 57—57 of FIG. 59.

FIG. 59 is a plan view of the crimping head with the strap gathering jaw closed.

FIG. 60 is a diagrammatic view of the hydraulic control system.

DESCRIPTION OF THE PREFERRED EMBODIMENT

At the outset, it should be explained that the present baling apparatus is designed to bale or bundle paper bags, although obviously the apparatus could be used for baling other products. Paper bags are usually formed so that the bottoms of the bags may comprise eight or nine thicknesses of paper, while the upper por-

tions of the bag are usually of four thicknesses. As a result, when bags are placed in superimposed relation, they form a wedge shaped mass as indicated in FIGS. 1 to 4 of the drawings. In order to form a stack which is of generally uniform height at both ends, the bags are stacked in groups or "hands" each of which may contain perhaps 25 bags. In order to simplify the task of alternately reversing the ends of the hands, the bags may be directed from the bag making machine to a collator 10 which delivers the hands of bags to a conveyor with the ends of the hands alternately reversed. The collator is not illustrated in the drawings.

FIGS. 1 through 10 of the drawings show the apparatus in block form in order to provide a simple indication of what takes place from the time the hands of bags are delivered from the collator until the stacks are discharged in baled form. FIG. 1 of the drawings indicates diagrammatically a conveyor identified by the numeral 10 which is conveying the alternately related hands A of bags to a position beneath a stacker and accumulator which is diagrammatically illustrated in this figure by the arrow B. The hands of bags A are delivered one at a time to the stacker and accumulator 20 and are elevated by the stacker B until a stack of bags 25 of proper size is formed. The stack of bags may preferably be any even number of hands A to form a stack C which the accumulator is designed to accommodate. The letter D designates the entire apparatus in block form.

In FIG. 2 of the drawings the stack of the bags C is being forced by a cylinder plunger 11 into a hopper indicated in general by the letter E. The hopper E is provided with an open front side so that the bag stack may be readily inserted. Once in place, the stack of bags is initially partially compressed by means not illustrated in these figures, this compression tending to remove air from the bags, and to hold them from falling from the open front and sides of the hopper E. The hopper in its entirety is tilted upwardly and rearwardly as indicated by the arrow 12 so that the bags are held against the rear wall and bottom panel of the hopper.

From the position indicated in FIG. 3, the stack of bags is conveyed while still in its rearwardly tilted form into a compression unit by a carriage which is diagrammatically illustrated by the arrow F. The carriage is actually a movable frame which slides the stack along supports coplanar with the tilted rear wall of the hopper and the bottom wall thereof. The carriage straddles the stack, and remains in position during the compression operation.

As indicated in FIG. 5 of the drawings, a compression unit G acts to compress the stack of bags C to a fraction of their original size. As will be later described, the compression unit includes a compression plate operated by a piston and cylinder to force the bags against a fixed platen at the bottom of the stack. As will be also later described in detail, the compression unit 60 includes a strapping unit designed to attach a pair of straps in stack encircling position while the stack is under compression.

In FIG. 6 of the drawings a pair of strap feeding chains are forced in tracks 14 in the direction of the arrow shown in the left part of FIG. 6. At the completion of this operation, means are provided for clamping the ends of baling straps to the ends of the chains bear-

ing the arrow points in FIG. 6. As indicated diagrammatically in FIG. 7 of the drawings, the direction of movement of the chains in the tracks 14 is then reversed, and the straps which had been clamped to the ends of the chain are then drawn completely about the compressed stack C. The ends of the strap are secured together and serve to hold the straps in bundle encircling position after the compression in the compression unit has been released as is indicated in FIG. 8 of the drawings.

The position of the carriage F is then reversed, carrying the baled bundle C over a tilted plate on the rear of the hopper E, which guides the bundles C to a discharge conveyor or other suitable discharge means. These steps are designed to indicate merely diagrammatically the position of the bags during the stacking, compressing, and other steps of the baling process.

STACKER AND ACCUMULATOR

The stacker and accumulator B are diagrammatically illustrated in FIG. 12 of the drawing. The conveyor 10 indicated in FIG. 1 of the drawings forces each hand of bags onto a dead plate 23, the conveyor 10 operating intermittently. Further movement of the conveyor 10 in the direction of the arrow 24 forces the foremost hand of bags onto a plunger plate 25 mounted on the upper end of the plunger 26 and against a guide plate 27, which limits the movement of the hand of bags. The plunger 26 is operated by mechanical linkage which is cam driven by the collator not shown in the drawings. The plunger 26 raises the hand of bags past a pair of opposed hinged plates 29 and 30 which are hingedly connected to fixed portions of the frame along parallel hinges 31 and 32. The hand of bags is elevated until the under surface of the hand is above the broken line level 33. The plunger 26 then moves downwardly, lowering the hand of bags until it rests upon the hinged plates 29 and 30. The plunger 26 continues downwardly into the position indicated in FIG. 12 to receive a second hand of bags. This operation continues until a predetermined number of hands have been elevated which is sufficient to fill the stacker accumulator B. A counter 34 is actuated by each pivotal movement of the plate 30 so as to count the proper number of hands.

The stacker accumulator B includes side plates 35, one of which is shown in FIG. 12 and a top panel 36 which limits the upward movement of the stack of hands in the accumulator. A pusher plate 37 is mounted upon a piston rod 39 actuated by a cylinder 40. When the proper number of hands have been accumulated, the vertically movable plunger plate 25 remains in elevated position at the broken line 33 while the pusher plate 37 forces the stack of bags into the hopper E.

THE HOPPER

The hopper E includes a bottom wall 41, a right angularly extending vertical rear wall 42, and a top wall 43. The bottom wall 41, and the top wall 43, are provided with grooves 44 and 45 therein for a purpose which will be later described. Lugs 46 extend upwardly from the top wall 43 to pivotally support one end of a cylinder 47 having a reciprocal piston rod 49. A clamping plate 50 is hingedly connected to the top wall 43 by a hinge 51, and the plate 50 includes a lug 52 pivotally

attached at 53 to the piston rod 49. This clamping plate 50 is hinged downwardly by the piston 49 when the stack of bags has been fed into the hopper E so as to hold the bags engaged in the hopper while the hopper is being tilted.

The hopper E is supported by a pair of parallel plates 54. The plates 54 are connected by a channel member 59. As indicated in FIG. 12, the plates 54 are somewhat L-shaped in form including upwardly and forwardly extending legs 60 welded or otherwise secured to the hopper bottom 41, and right angularly extending legs 61 having edges 62 welded or otherwise secured to the rear panel 42 of the hopper, the ends of the legs 61 supporting a plate 63 rearwardly of the rear wall 42 of the hopper and at an angle of approximately 45° with respect thereto.

The frame of the apparatus which may be indicated in general by the numeral 64 includes a pair of parallel frame members of generally similar form. These frame members are on opposite sides of the hopper E and the general form thereof is indicated in FIG. 12. The spaced parallel frame members 65 include parallel uprights 66 and 67 connected at their upper ends by cross connecting members 69 and 70, the cross connecting member 69 of the right hand member 65 being above the level of the cross connecting member 70 of the left hand member 65 as viewed in FIG. 11. The frame members 65 each also include an inclined cross brace 71 which angles upwardly and forwardly from the rear upright 66 to the forward upright 67 and is at generally a 45° angle with respect thereto. A second angled brace 72 extends upwardly and rearwardly from the lower portion of the front upright 67 and is welded to the angle brace 71 at its upper end. The two parallel frame members 65 are connected by transverse channels 73 near the lower ends of the uprights, and by parallel channels near the ends of the uprights which will be described.

Lugs 75 extend upwardly and forwardly from the inclined braces 72 and support a pivot shaft 76 extending through the angular legs 60 of the hopper supporting plates 54. A cross member 77 connects the frame members 65 and supports a bracket 79 which is pivotally connected to a cylinder 80 by means of a pivot 81. The channel member 59 is also provided with a central lug 82 pivotally connected to the piston rod 83 reciprocal in the cylinder 80 by a pivot 84. Thus upon movement of the piston rod 83, the entire hopper E may be tilted from the upright position shown in FIG. 12 in full lines to the tilted position indicated partially by the dotted outline in this Figure.

FIGS. 13 and 13A of the drawings show an alternate form of hopper E' which is generally similar to the hopper E with the exception of the fact that means are provided for precompressing the bags which takes the place of the clamping plate 50 and its operating mechanism. In the arrangement illustrated in these Figures, an upwardly extending generally inverted U-shaped frame 85 is mounted on the top plate 43 of the hopper to support a vertical cylinder 86. A precompression plate 87 is mounted on the lower end of the piston plunger 89 of the cylinder 86. The precompression plate 87 is rectangular in form and is held from rotation about the piston rod axis by suitable slide guide means such as 90. The hopper E' has the ad-

vantage over the hopper E in that the stack of bags may be compressed sufficiently to drive much of the air from the bags and between the bags in the stack and will therefore lighten the task of the main compression unit in completing the compression operation.

The main purpose of the hopper construction which has been described is to swing the stack of bags from stack receiving position a tilted position within a carriage F so that the clamping pressure on the bags may be released and the bags will be held by gravity against the rear wall 42 of the hopper and the bottom plate 41 thereof as the carriage moves the stack from the hopper to the compression unit. The carriage is designed to hold the sides of the stack in proper relation from the time the stack of bags is tilted into the carriage until the stack is completely baled and returned to discharge position.

THE CARRIAGE

The carriage is constructed as is best illustrated in FIGS. 12 and 12A of the drawings. The carriage includes a pair of parallel bearings 92 connected in parallel relation by a suitable connecting member 93. Rollers 94 are pivotally supported at opposite ends of the bearings 92. An upright frame support 95 extends downwardly from each bearing, the uprights being in spaced parallel relation, and being spaced apart a distance slightly greater than the width of the stack of bags and the hopper E. Angular braces 96 tend to hold the uprights rigid. Each upright 95 supports a generally rectangular frame 97, the frames 97 being parallel and spaced to accommodate the hopper and the stack of bags therebetween. While the construction of the frames 97 may be varied, in general they include a series of spaced parallel bars 99 held in position by right angularly extending connecting members 100. The bars 99 and connecting members 100 are arranged at an angle of approximately 45° to the vertical or parallel to the rear wall 42 and bottom wall 41 of the hopper E in its tilted position.

The ends of the bars 99 which are closest to the rear panel 42 of the hopper are preferably slightly longer than the other bars 99 to provide slightly extending ends 101 designed to extend into the grooves 44 and 45 in the bottom and top walls 41 and 43 of the hopper E. The purpose of this arrangement is merely to insure the engagement of all of the bags in the stack C by the carriage when the stack is being shifted from the hopper to compression position.

The carriage is moved by the mechanism indicated in FIG. 14 of the drawings. An end frame member 103 which is virtually identical with the frames 65 is supported in parallel relation to the frames 65, and is connected thereto by longitudinally extending channels 104 and 105 near the upper ends thereof, as well as by the channels 73 near the lower ends thereof. Tracks 106 connect the cross members 70 and 108 of the end frames of the series, the top cross member 69 of the intermediate frame member 65 being above the level of members 70 and 108. The carriage is designed to move along the parallel tracks 106, the rollers 94 riding on the upper surfaces of the tracks. Rollers 107 may be mounted on lugs 109 on the carriage, the rollers 107 being arranged on vertical parallel axes, and the surfaces of the rollers engaging the inner opposed surfaces of tracks 106.

A bracket 110 is mounted on the frame channel 105 and pivotally supports a toggle lever 111, the other end of which is pivotally connected at 112 to one end of a second toggle lever 113. The other end of the second toggle lever 113 is pivotally connected at 114 to suitable means on the carriage F. The pivotal connection 114 is preferably at the left hand end of the carriage F as viewed in the Figures. A cylinder 115 has one end pivotally connected to a bracket 116 on the frame member 105, and a clevis 117 on the piston rod 119 of the cylinder 115 is pivotally connected to the toggle lever 111. Outward movement of the piston rod 119 will pivot the toggle links from the full line position to the broken line position in FIG. 14, and moving the carriage F from one extreme position to another. This movement transfers the bag stack from the hopper to compression position.

COMPRESSION UNIT

The compression unit is designed to receive a stack of bags carried into the compression unit by the carriage, and to compress the stack of bags to approximately 40 percent their original size. The compression unit also incorporates means for drawing a pair of straps about the compressed bundle, clamping the ends of the straps together and cutting the strap before releasing compression so that the bale may be discharged by the carriage. The construction is perhaps illustrated in FIGS. 16, 22, 22A, 23 and 30.

As is indicated in FIG. 16, an I beam 121 is welded or otherwise secured between the end frame member 103 and the intermediate frame member 65. The central web 122 is arranged at an angle of 45° to horizontal, and is located in parallel relation to the bottom platen 123 of the compression unit, the upper surface of which is coplanar with the bottom panel of the hopper E in tilted position thereof. The web 122 of the I beam 121 supports a compression cylinder 124 having a piston and piston rod 125 which supports a compression plate 126. The central portion of the compression plate 126 is designed to ride along supporting means, the forward surface of which is coplanar with the rear wall 42 of the hopper E when the hopper is in its tilted position.

FIG. 16, as well as FIG. 22A, shows the compression unit in its open position to receive a stack of bags. The compression plate is shown in cross section in FIG. 16A of the drawings. As indicated, the face portion of the plunger is divided into three sections mounted upon a base plate 127. The central section 129 is provided with an L-shaped groove 130 communicating with the left edge thereof. The side portions are generally channel shaped members 131 having the ends of the channel sides welded or otherwise secured to the plate 127. The right hand member 131 includes a groove 130 similar to that in central section 129. The center portion 129 is spaced from the side portions 131 to provide grooves 132 therebetween as will be later described. As indicated in FIGS. 22, 22A and 26, corner blocks 133 are secured along the upper and lower edges of the central portion 129 and of the right hand member 131 of the compression plate. These blocks 133 have arcuate grooves 134 which form a continuation of the chain groove 130.

As indicated in these same Figures, the bottom platen 123 is also provided with a corner block 135

which forms a continuation of a chain groove 136 extending through the platen and communicating with the surface thereof by a groove 137. There are actually two such chain grooves extending into the platen 123, these grooves being located near opposite ends thereof. A fixed upper side wall 139 is supported by the corner block 135 and extends in right angular relation to the surface of the platen 123. The side wall 139 is provided with chain grooves 140 therein which form a continuation of the groove 141 in the corner block 135.

As will be noted in FIGS. 22 and 26 of the drawings, when the compression plate 126 is in projected position to compress the stack of bags, there are two continuous chain tracks extending entirely about the stack of bags, one of which is shown in these Figures. One side of each of these tracks extends through the compression plate 126 and the attached corner blocks 133. A second side of the track is provided in the wall 139 and attached corner block 135. A third side of the track extends through the platen 123. The fourth side of the track includes a double track arrangement which includes a strap feed apparatus 142, and a chain guide or retractable corner block and wall section 143. This retractable corner block and wall section includes an inner chain track 144 and corner section 145 as well as an outer track section 146 which is aligned with the portion of the track extending through the strap feed apparatus 142 and the corner block 134 in one position thereof. In its other extreme position, indicated in FIG. 30 of the drawings, the corner block and wall section 143 is retracted to expose portions of the straps so that these portions may be clipped together.

STRAP FEED APPARATUS

In general, when the compression plate is in compression position, completing the chain track about the stack of bags, a pair of chains are driven by sprockets to progress entirely about the stack of bags until the ends of the chains overlap other portions of the same chains. Clamps are provided on the ends of the chain which engage the ends of baling straps fed from reels of strapping material. The chains are then drawn in a reverse direction, pulling the straps entirely about the bale until the clamped ends of the tape overlap adjoining portions of the straps. The ends of the straps are then clipped together to hold the bale under compression.

In order to prevent any interruption in the chain guiding grooves when the compression plate 126 is in its compression position, overlapping guides are provided on the corner blocks 133 and 134, and on the side 139 and apparatus 142 respectively. These blocks are of the type indicated in FIGS. 27, 28 and 29. A pair of connected blocks 149 are attached to each of the corner blocks 133 and are provided with a pair of spaced parallel prongs 150 which are designed to form a continuation of the curved track portions 134 of the corner blocks 133, and a third prong 151 which is intermediate the planes of the prongs 150 and arranged on the opposite side of the chain track from the prongs 150. The cooperable blocks 152 which are mounted upon the wall 139 and the strap feed apparatus 142 respectively includes a pair of parallel spaced prongs 153 and an opposed single prong 154. When the compression plate 126 is in closed position, the various

prongs overlap to form a continuous chain guide. As is indicated in FIG. 27 of the drawings, each prong 151 extends between the pair of prongs 153 of each block 152, and the single prong 154 extends between the spaced prongs 150, the overlapping prongs forming a continuation of the walls of the chain groove. FIG. 27 of the drawings shows a link of one of the chains 155 between the overlapping prongs 150, 151, 153, and 154.

Chain guides 158 and 158A are provided to control the movement of the chains 155 between the chain guide 180 and the retractable corner block and wall section 143. These guides telescope into the section 143 and comprise a single bar 158 engaging the center of the chain, and a pair of spaced bars 158A engaging the opposite side of the chain.

The chains 155 are driven by sprockets 156 mounted upon shafts 157 which are supported in axial alignment. Each shaft 157 is provided with a gear 159 (see FIG. 26) which is engaged by a gear rack 160 for rotation thereby. As is diagrammatically illustrated in FIG. 17 of the drawings, the racks 160 are connected by a yoke 161 which in turn is connected by a clevis 162 to a piston rod 163 secured to a piston 164 mounted in a cylinder 165. As the piston 164 is reciprocated in the cylinder 165, the racks 160 are moved simultaneously in suitable supports 166, rotating the gears 159 which act through the shafts 157 to rotate the sprockets 156 and to move the chains 155.

The free ends of the chains 155 are provided with strap clamps 167 which are best illustrated in FIGS. 33 and 34 of the drawings. The strap clamps 167, as shown in FIG. 33, are offset from the chain itself, and each clamp 167 is connected to its chain by a bracket 169 which is pinned to the end link of the chain by a suitable pin 170. As indicated, the forward end of each clamp 167 is bifurcated, one side of the bifurcated end being pointed as indicated at 171. A trapezoidal slot 172 is provided in each clamp with the narrow side of the slot adjoining the slot opening 173. A wedge 174 having a toothed strap engaging surface 175 is mounted in the slot 172, and is urged toward the open narrow end of the slot by a small spring 176. The structure is such that the strap 177 may engage between the wedge shaped jaw 174 and the wall 179 of the slot 172. The insertion of the tape into the clamp tends to push the jaw 174 toward the wider end of the slot. However, once the tape is engaged between the jaw 174 and the clamp wall 179, any reverse movement tending to disengage the tape from the slot will cause the wedge shaped jaw 174 to slide toward the open end of the slot and to tightly clamp the tape.

As will be described, a chain guide support 180 is pivotally supported on each shaft 157 for supporting a corresponding chain guide 143. The chain guide 143 is provided with supporting slides 181 slidable in the support 180 and which permit the chain guides 143 to move from the retracted position indicated in FIG. 30 of the drawings, to the projected position indicated in FIGS. 22 and 26 of the drawings. As indicated in these Figures of the drawings, the chain guide 143 includes an outer chain track 146 which is in alignment with the curved track area 134 in the corner block 133 near the left hand side of these Figures. A second or inner chain track 144 is aligned with the curved track portion 145

forming a part of the chain guide, and this curved track portion moves into alignment with the track portion 136 in the platen 123 when the chain guide is in the projected position indicated in FIGS. 22 and 26.

STRAPPING APPARATUS

When the stack of bags reaches compression position and is compressed, the chain guide 143 is in the position indicated in FIG. 30 of the drawings, with the exception of the fact that the seal crimping mechanism is retracted and out of the path of movement of the chain guide 143. A spring 184 is connected at one end by a suitable pin 185 to a portion of the chain guide 180 and is connected by a pin 186 to a stop lug 187 of the platen 123. However, the weight of the chains 155 and the fact that sprockets 156 are held from rotation, is sufficient to overcome the force of the spring 184 and the chain guide remains in the tilted position illustrated in FIG. 30 when the chains are not in motion.

As soon as the gear racks 160 are moved to rotate the aligned shafts 157, the sprockets 156 are rotated in a counter clockwise direction, and the downward pull of the chains 155 is overcome. This causes the chain guide 143 to tilt about the axis of the shafts 157 until the track portion 146 is aligned with the section of the track extending through the strap feed apparatus 142. The movement of the chain and the force of the spring 184 combine to advance the chain guide 143 from the position indicated in FIGS. 22A and 30 of the drawings to the position indicated in FIGS. 22 and 26. This advancement of the chain guide 143 continues until the curved track portion 145 in the chain guide 143 aligns with the track 136 in the platen 123.

In order to prevent the premature movement of the chain 155 from the chain guide 143, a chain locking means illustrated in FIGS. 24 and 25 is provided. This locking mechanism is embedded in the body of the chain guide 143 and includes a locking lever 190 pivotally supported at one end as shown at 191 to the chain guide 143 and having its free end 192 engaged against the side of the chain 155 between adjoining links. The lever end 192 is urged into this position by a spring 193. A plunger 194 is slideably supported in a bore 195 which intersects the chamber 196 in which the lever arm 190 is located. The plunger 194 is urged into a projected position by a spring 197. The plunger 194 is provided with annular groove formed by a frusto-conical plunger portion 199, and a reduced diameter adjoining portion 200. The plunger 194 projects from the end of the chain guide 143 and is designed to engage into a cooperable socket 201 in the strap feed and shearing device 142.

The lever arm 190 normally holds the chain from movement in the chain guide 143 until the chain guide reaches its extreme position indicated in FIGS. 22 and 26. At this point, as the chain guide 143 approaches the strap feed and clip forming device 142, the plunger 194 is retracted in the direction of the arrow 202, the frusto-conical portion 199 of the plunger acting as a cam and engaging the lever arm 190, swinging the lever in the direction of the arrow 203 in FIG. 24, swinging the lever arm 190 in a clockwise direction and disengaging the lever end 192 from the chain. Thus, when the chain guide is in fully advanced position, the chain is released and is guided into the strap feed device 142.

or into the track section 204, forming a part of this device 142.

Movement of the chains 155 continues, forcing the chain through the curved track 134 in one corner block 133, through the straight track portion 130 in the compression plate 126, about the curved track section 134 in the other corner block 133, through the track 140 in the wall 139, through the curved track portion 141 in the corner block 135, through the track section 136 in the platen 123, through the curved track section 145 in the chain guide 143, and through the straight track section 144 in the chain guide 143 until the clamp 167 at the end of each chain 155 reaches strap engaging position. The strap extends into the clamp 167 of each chain, and the racks 160 start in a reverse direction, pulling the strap completely about the compressed stack of bags C. FIG. 26 of the drawings shows one of the chains 155 in a partially retracted position drawing 20 the strap 177 about the bags C.

It will be noted that while the chains 155 are confined within the chain tracks which have been described, the clamps 167 extend laterally from the chains and extend over slots such as 132 and 137 in the platens 126 and 123, and a similar slot 168 in the wall 139, these slots being located in the inner surface of the various walls and corner blocks so that the straps 177 may be wrapped about the stack. This is true of the tracks in the compression plate 126, the wall 139, the platen 123 and the various corner blocks.

The retraction of the chains 155 continues until the chains reach the position indicated in FIG. 22 of the drawings. Further retraction of the chains acts to retract the chain guides 143 and to tilt the end of the chain guides from which the clamps extend into the position shown in FIG. 30 of the drawings, this action bringing the strap end in close proximity with the portion of the strap 177 which it overlaps.

Once the strap has been drawn completely about the compressed stack of bags, means are provided for cutting the strap, preferably after the ends have been attached together, and means must also be provided for advancing the cut end of the strap into the chain clamps during the following cycle. This mechanism is indicated in FIGS. 18, 31, 32 and 35 of the drawings.

As indicated in FIG. 18, the portion of the frame of the apparatus lying rearwardly and beneath the stack of bags during compression includes a pair of spaced inclined channels 205 connected by a bed plate 206 forming a part of the fixed frame of the apparatus. Coplanar stack engaging plates 207, 209 and 210, are held in spaced relation to the bed plate 206 by spacer strips 211, spacer strips 212, and the channels 205. A space is provided between the plates 207, 209 and 210 for the purpose of accommodating the strap advancing and cutting apparatus 142, one of which is shown in enlarged detail in FIGS. 31, 32 and 35.

The strap advancing apparatus 142 is mounted upon a fixed bracket 213 by a pivot 214. The device 142 comprises an elongated block-like body 215 which, as indicated in FIG. 22 of the drawings, is provided with a pair of spaced pivot portions 216 through which the pivot 214 extends.

The elongated body 215 is provided with a chain track communicating with one side wall of the body by means of a slot 217. When the compression unit is

closed, the chain track 204 forms a continuation of the chain track extending about the compressed bundle as has been described. The body 215 is provided with an elongated slot or aperture 219 extending therethrough and through which the strap 177 is threaded. As indicated in FIG. 35 of the drawings, a shearing lever 220 is hingedly connected at 221 to the outlet end of the body 215. The shearing lever 220 is provided with a shearing blade 218, which is designed to shear off the tape as it leaves the slot 219. The shearing lever 220 is pivotally connected at 222 to a second toggle lever 223 fixedly connected by a pivot 224 to the spacing member 212. The center pivot 222 of the toggle lever arrangement is connected by a link 225 to a clevis 226 on a piston rod 227 extending into a cylinder 229. The cylinder 229 is fixedly mounted to the frame by a bracket 230.

When the piston rod 227 is moved downwardly by the piston 231 in the cylinder 229, the shear lever 220 and toggle lever 223 move into alignment, pivoting the shear lever and shearing off the strap at the end of the body 215. During this action, the body 215 is swung slightly in a counter clockwise direction as viewed in FIG. 35, about the axis of the supporting pivot 214. A further downward movement of the piston rod 227 draws the shear lever 220 and toggle lever 223 past dead center position and into angular relation. This action tilts the body 215 in a clockwise direction about the pivot 214 so that the slot 217 in the side of the block-like body 215 is tilted to open upwardly. The purpose of this arrangement is to permit the release of the strap which has been drawn by the chain clamp through this slot 217. In other words, the clockwise tilting of the body 215 widens the space between the top of the body 215 and the right hand edge of the plate 207 to simplify the release of the lower portion of the overlapping straps.

The body 215 of the strap shearing and advancing mechanism 142 includes an elongated chamber 232 designed to slideably accommodate a generally rectangular block 233 overlying the strap 177 in the strap slot 219. As is indicated in FIG. 31, the block 233 is mounted upon a piston rod 234 connected to a piston 235 reciprocal in a cylinder 236. FIG. 31 shows the block 233 in its normal retracted position. As shown in FIG. 32, the block 233 is provided with a generally trapezoidal notch 237 which accommodates a wedge shaped jaw 239 normally urged toward the small dimension end of the notch 237 by a spring 240. Movement of the strap 177 in a right hand direction beneath the jaw 239 is not impeded, as the frictional engagement with the jaw 239 tends to move the jaw toward the large diameter end of the notch. However, when the block 233 is moved to the right in the direction of the arrow 241, the jaw will grip the strap and advance the strap into the adjoining chain clamp 167 which is at this point in strap receiving position.

FIG. 21 diagrammatically illustrates once the strap 177 has been engaged in one of the chain actuated strap clamps 167, it would be extremely difficult to withdraw the clamped end of the strap from the clamp by a longitudinal action. Accordingly, a means is provided indicated in general by the numeral 242 to engage the strap near the clamped ends thereof, and to force the tape laterally from the clamps. The location

of this means is indicated in FIG. 16 of the drawings, and the construction itself is diagrammatically illustrated in FIG. 21.

As is indicated in this figure, a pair of brackets 243 and 244 extend rearwardly and downwardly from the plates 207 and 209 to support a pair of rods 245 in parallel relation. The rods 245 are connected at one end by a crosshead or yoke 246. A cylinder 247 containing a piston 249 is mounted upon a third bracket 250 extending rearwardly and downwardly from the plate 210. A pair of arms 251 are mounted upon the rods 245 for movement therewith. The piston 249 is connected to the crosshead 246 by a piston rod 252. The arms 251 are provided with fingers 253 which are located laterally from the straps 177.

At the completion of the strap clamping fluid is directed to the cylinder 247 to move the rods 245 to the left as viewed in FIG. 21. The fingers 253 forming a part of the arms 251 engage the straps 177 adjoining the clamped end thereof, and force the straps laterally out of the clamps 167.

CLIP FEED AND FORMING DEVICE

In general, the clip feed and former is designed to form channel-shaped clips formed of thin metal or other suitable formable material, the sides of which may be bent in a manner to form a seal encircling two layers of the baling strap 177 to secure the straps in bale encircling position. The steps of forming the clip are best illustrated in FIGS. 37a, 37b, 37c and 37d of the drawings. The clip forming material is shown as comprising an elongated strip 255 which is normally supplied from a pair of side by side reels which will be described. The strip 255 is preformed with opposed pairs of notches 256 which are arranged at regular intervals extending into the side edges of the strip. The strip 255 is fed by suitable means engaging the notches 256 into a suitable die which bends the sides of the strip 255 upwardly into parallel relation between the notches 256 to form channel-shaped sections. These sections are then cut apart at the notches and the channel-shaped clips are fed into a suitable crimping apparatus. FIG. 37c is designed to show one of the channel-shaped clips with the sides 257 in generally parallel relation. FIG. 37d shows the finished clip which has been bent to form a flat tube, the sides 257 having been folded into edge abutting relation, and the body crimped to increase the frictional engagement of the clip with the straps which are not shown in this Figure. For the purpose of identification, each formed clip will be identified in general by the numeral 259.

The clip forming apparatus may be seen in general in FIG. 16 of the drawings and is identified by the numeral 260. Frame cross member 206 supports the clip forming means on the frame, and the notched strip 255 is fed to each device 260 from a suitable reel 262. Obviously, as two bale encircling straps are employed, there are actually two seal forming units and two reels 262 to accomplish the result.

The bracket 261 includes a base plate 263 extending parallel to the elongated body forming lower section of 264 of the feed mechanism and clip former and supports a cylinder 265 including a piston connected to a piston rod 266. The rod 266 supports a pressure plate 267 best illustrated in FIG. 36 of the drawings.

Reciprocation of the piston in the cylinder 265 is designed to first actuate the feeding mechanism and then the clamp forming and cutting mechanism.

As is indicated in FIG. 37, a bearing block 269 on one side of the body 264 supports a push rod 270 having a right angularly turned end 271 extending through an elongated slot 272 in a crank arm 273 secured to a shaft 274 rotatably supported in a bearing 275, mounted on the top section of the apparatus 260. The push rod 270 is normally held in a lowered position by a spring 276 secured between the push rod arm 271 and a fixed pin 277. A lever 279 is fixed to the shaft 274 and extends into an elongated slot 278 in the upper portion 281 of the clip feeding and forming mechanism. A pivot 280 pivotally connects the lever 279 to a strip pusher 282 the operation of which is indicated in FIGS. 39 to 43 inclusive.

The strip pusher 282 is perhaps best illustrated in detail in FIG. 38 of the drawings. This device comprises a channel-shaped body having parallel sides 283 between which is formed a slot having a flat base 284. The under surface is defined by a forwardly and downwardly inclined surface 285, and a rearwardly and downwardly inclined surface 286. A pair of spaced tapered teeth 287 are provided at the apex between the inclined surfaces 285 and 286. These teeth 287 are designed to engage into the notches 256 of the strip 255, and have vertical forward surfaces 289 which engage the edges of the notches 256 and force the strip forwardly beneath the upper portion 281 of the clip former and feed device 260. The rear surfaces 290 of the teeth 287 are inclined to permit the strip pusher to slide over the surface of the strip upon return movement thereof.

The channel sides 283 are provided with aligned apertures 291 which accommodate the pivot 280 connecting the strip pusher to the operating lever 279. A cylindrical slide guide or pin 292 extends through a pair of vertically elongated slots 293 in the channel sides 283, the pin 292 being anchored in a block 294 freely supported in the groove between the channel sides 283. A spring 295 is interposed between the forward end of the block and the base 284 of the channel, the spring being recessed in sockets in the opposed parts so as to remain in position. The ends of the pivot shaft 292 project laterally beyond the sides of the channel walls 283 for a purpose which will be described.

In order to provide a complete understanding of the clip feed and forming device, FIG. 36 of the drawings shows the upper forming section 281 which is supported in fixed position, and the lower die section 264 which is vertically movable relative to the upper die section 281. FIGS. 36a, 36b, 36c, 36d and 36e are sections through the apparatus 260, FIG. 36a looking upwardly at the under surface of the upper section 281, and 36b looking downwardly from the upper surface of the lower section 264. As shown in these sections, they are held together by bolts 297 which are threaded into the upper section 281. The heads 299 of these bolts are slidable in cylindrical recesses 300 in the bottom section 264, one of which is indicated in FIG. 36c. The bolts are held in position by suitable shoulders to prevent separation of the two sections. Springs 301 are engaged in sockets 298 in the bottom section 264, and normally urge the two sections 281 and 264 apart.

A pair of parallel flanges 302, the outer edges of which are spaced apart a distance substantially equal to the width of the clip forming strip 255, extend downwardly from the upper section 281 to extend longitudinally thereof. The strip pusher 282 is slidable between these flanges 302 which act as a guide therefor. FIGS. 39 through 43 inclusive are designed to illustrate the manner in which the pusher 282 is operated. FIG. 39 shows the position of the crank arm 272 and lever arm 279 as the pusher starts its operation. FIG. 40 shows the pusher 282 in its starting position, and indicates the slots 303 in the flanges 302 which guide the strip pusher in its movement. One of these slots is shown in each of FIGS. 40, 42 and 44, it being understood that similar slots 303 are provided in each of the flanges 302. It should be stated that the portions of the pins 292 which extend beyond the sides of the pusher 282, slide in the slots 303 and are guided thereby.

As indicated in FIG. 40 of the drawings, as the pusher 282 starts its movement to the left, the teeth 287 engage in a pair of opposed notches 256 in the edges of the strip 255. FIG. 41 shows the crank arm 272 and the lever 279 in an intermediate position, and FIG. 42 shows the pusher in a corresponding position. As will be noted, the tracks 303 include upwardly offset end portions 304 connected to the main portion of the slots by inclined ramps 305. As the pusher 282 moves from the position shown in FIGS. 41 and 42 to the position shown in FIGS. 43 and 44, the pins 292 ride up the ramp portions 305 and the teeth 287 are raised out of engagement with the notches 256. When in this position, the block 294 through which the guide pins 292 extend may be pivoted slightly by the springs 295.

Upon return movement of the lever 279, the pusher 282 is moved in a reverse direction, and the teeth 287 may slide over the surface of the strip 255. The slots 293 in the opposite walls of the pusher 282 permit the slight elevation of the pusher 282 which is necessary to return the strip pusher to its original position without undue friction against the strip 255.

A male forming die 306 (FIGS. 36a, 36d, and 36e) extends downwardly from the under surface of the upper section 281, this male die 306 having its under surface coplanar with the under surfaces of the flanges 302. Thus, the advancement of the tape strip may continue from beneath the flanges 302 to a position beneath the male die 306. As indicated in FIGS. 36b, 36c and 36d, a strip supporting platform or table 307 is supported in a generally rectangular groove 309 in the upper surface of the lower die section 264. The table 307 is supported by bolts 310, one of which is shown in FIG. 36c, the bolts 310 being encircled by springs 311 which urge the table 307 into coplanar relation with the upper surface of the die section 264. The bolts 310 are limited in their movement by bolt heads 312 which engage shoulders 313 to limit the upward movement of the table. The table 307 is substantially equal in width to the width of the strip 255.

A female forming die 314 is removably fixed in the groove 309 beyond the table 307 as shown in FIGS. 36b, 36d, and 36e. The die 314 is a channel-shaped structure including a base portion 315 and upwardly extending side walls 316 having inwardly and downwardly tapering upper ends 317 designed to assist

in folding the side edges of the strip 255 about the male die 306 and within the female die 314. As indicated in FIG. 36b, the table 307 is provided with a relatively narrow continuation 319 which is vertically slidable in a slot 320 in the die 314. The purpose of the extension 319 is to form support for the center portion of the strip 255 during the forming operation and to hold the bottom of the channel-shaped clip at right angles to the side flanges thereof, and to eject the clip from the female die after forming.

As indicated in FIG. 36b a cutter blade 321 is attached to the bottom die section 264 at the end of the die 314. As the strip 255 is plunged into the female die 314, the strip 255 is sheared off by the blade 321 to form a separation between the portion of the strip 255 extending through the strip feeder and forming mechanism and the portion of the strip which has been previously formed and which has been fed beyond the cutter blade 321.

A clip advancing mechanism is indicated in FIGS. 36, 45, 46, 47, and 48. A T-shaped bar 322 projects from the outlet side of the die, and the ends of the crossbar 323 of the T-bar are connected by spaced uprights 324 to a cross member 325 which is bolted or otherwise secured as indicated by the countersunk bolts 326 to the top section 281 of the apparatus. The stem 327 of the T-shaped bar is supported with its upper surface 329 flush with the upper surface of the lower die section 264 in retracted position thereof so that clips leaving the clip forming die may slide directly onto this surface 329.

A clip advancing carriage 330 is provided with a downwardly extending projection 331, at one end thereof which is provided with a slot 332 which straddles the stem 327 of the T-shaped bar 322. A piston rod 333 is provided with a threaded end 334 which extends into the cross member 325. The piston rod 333 extends into a hollow chamber 335 in the carriage 330. A piston 336 is provided on the end of the piston rod 333 and is slideable longitudinally in the chamber 335. The introduction of fluid under pressure to the left of the piston 336 in the chamber 335 acts to urge the carriage 330 to the left into the position shown in FIG. 48. The introduction of fluid to the right of the piston 336 retracts the carriage 330 to the position shown in FIG. 45.

A spring 337 is provided with an angularly turned end 339 which is clamped against the crossbar 325 by a lock nut 340 on the piston rod 334. The spring 337 extends into each clip 259 and holds the base of the clip against the upper surface 329 of the stem 327 of the T-shaped bar 322. Thus, as each clip is fed longitudinally from the forming die, it is held against the T-shaped bar 322. The clips 259 are held in longitudinal alignment as indicated in FIG. 47 with the side flanges 257 of the clips directed upwardly. During the feeding operation, there is always one clip beneath the spring 337, and a second clip has been forced by the adjoining clip to a position overlying the end of the T-shaped bar stem 327.

A flange 341 extends downwardly from the under surface of the carriage and acts as a guide for one side of the clip 259. A lug 342 extends downwardly from the carriage 330 in spaced relation to the flange 341. A leaf spring 343 is supported by the lug 342 and is designed

to engage the wall 257 of the clip 259 which is opposite that engaged by the flange 341. As each clip 259 is pushed through the clip former and over the T-shaped bar 322, it is resiliently engaged by the spring 343, thereby supporting each clip as it is moved into position over the crimping apparatus.

An ejector lever 344 is pivotally supported at 345, the pivot extending through the flange 341 and lug 342. The ejector 344 serves to eject the clip into the crimping apparatus when the carriage 330 is in the projected position illustrated in FIG. 48 of the drawings. The ejector 344 is shown in side elevation in FIGS. 45 and 48 of the drawings. The end of the ejector 344 is shown in enlarged form in FIG. 45a of the drawings.

The ejector 344 is urged downwardly by a spring 346 engaged in a socket 347 in the carriage 330. The ejector 344 is normally held in retracted position by a trigger 349 pivotally connected to the underside of the carriage 330 by a pivot 350. The trigger 349 is held in ejector engaging position by a spring 351. As indicated in full lines in FIG. 45a of the drawings, when the ejector is in retracted position, the trigger 349 engages a shoulder 352 on the ejector. However, when the trigger 349 is swung in a counter-clockwise direction as viewed in FIG. 47 of the drawings, the trigger is disengaged from the shoulder 352 and engages a second shoulder 353. In this position, the ejector 344 has stripped the clip 259 from the carriage 330 and has deposited it in the crimping apparatus which is indicated in general by the numeral 348. As is indicated in FIG. 48, the trigger 349 is automatically operated as the carriage 330 moves into position above the crimping unit 349, by engagement with a portion of this device.

The clips 259 are prevented from overtraveling by a shoulder 354 at the end of the carriage. The clips are automatically fed into position beneath the ejector by the movement of the adjacent clip being ejected from the forming die. Each clip is held in place upon the carriage 330 by the spring 343 until the carriage moves into position over the crimping device 348. At this position, the trigger 349 releases the ejector 344 which forces the clip into the crimping device. The carriage 330 then returns to its retracted position indicated in FIG. 45. This movement automatically swings the ejector lever 344 into retracted position, and the trigger 349 automatically re-engages the shoulder 352, resetting the ejector 344 so that the carriage is positioned to accept another clip.

CLIP CRIMPING APPARATUS

The crimping device 348 is shown in FIGS. 16, 20, 30 and 49 through 54 inclusive. The position of the crimpers with relation to the other elements of the structure is perhaps best illustrated in FIG. 16. FIG. 30 of the drawings shows the crimping device 348 in its extended position in readiness for crimping a seal about the overlapping ends of the strap 177. The crimpers 348 is supported by a cylinder 355 which is anchored to a suitable frame member 356. The general arrangement of the two crimpers and the operating mechanism therefore is best seen in FIG. 49.

A piston 357 within the cylinder 355 is provided with a piston rod 359 which projects from the cylinder end. A crosshead 360 is supported on the piston rod 359 for

movement in conjunction therewith. The crimper units 358 are mounted upon a connecting bar 361 which is slidably supported by rods 362, the rods 362 being fixed relative to the plate 361 but slideable with respect to the crosshead 360. Springs 363 encircle the portion of the rods 362 between the crosshead 360 and the connecting plate 361. As a result, when the connecting bar 361 moves upwardly and engages against fixed frame members 364, the movement of the connecting bar 361 stops, but the movement of the crosshead 360 continues.

The crimping elements 348 are mounted at opposite ends of the connecting bar 361. Angular front mounting plates 365 include horizontally extending portions 366 attached by bolts 367 to the front of the connecting bar 361, and generally similar angular rear mounting plates 369 are bolted to the rear of the connecting bar 361. Mounted between the mounting plates 365 and 369 are a series of crimping jaws and anvil plates which will be later described in detail.

As may be seen in FIGS. 49, 50 and 51, the front mounting plates 365 are provided with a pair of upwardly projecting tapered arms 370 between which the overlapping end portions of the baling strap is designed to extend when the crimping device is raised into the dotted line position indicated in FIG. 49. The two overlapping portions of the straps 177 are gathered to the bottom of each notch defined between the arms 370 by a hook-shaped lever 371 pivotally connected to the mounting plate 365 by a pivot 372. The hook-shaped ends 373 of the levers 371 are normally spaced laterally from the grooves between the arms 370 so as not to interfere with the movement of the straps into these grooves. Push rods 374 are pivotally connected to the levers 371 by pivots 375. The push rods 374 extend down through apertures 376 in the crosshead 360, and fit loosely enough through the apertures to permit slight angularity of the push rods relative to the crosshead. Washers 377, held from downward movement on the push rods 374 by pins 379 limit the upward movement of the push rods relative to the crosshead. Springs 380 encircle the push rods 374 and are engaged in sockets 381 coaxial with, and above, the apertures 376. Washers 382 encircle the push rods 374 and are held in place by pins 383.

The springs 380 urge the push rods 374 upwardly to the extent permitted by the stop washers 377. As the cross head moves upwardly, (beyond the point at which the connecting bar 361 stops) the push rods 374 move upwardly in unison, swinging the collecting levers 371 about their pivots 372 over the two overlapping tapes, clamping the tapes to the base of the groove between the arms 370. FIG. 50 of the drawings shows one of the levers 371 in its retracted position which it normally assumes. FIG. 51 of the drawings shows the lever 371 in its clamping position, holding the overlapping strap portions 177 in substantial face contact. The levers 371 remain in the clamped position shown in FIG. 51 during the operation of crimping the seal 259. When in clamping position, the washers 382 on the push rods 374 engage the undersurface of the mounting plates 365, and further upward movement of the crosshead 360 acts merely to compress the springs 380, the push rods 374 sliding in the apertures 376 as indicated in FIG. 56.

As indicated in FIG. 55 of the drawings, a rectangular plunger 384 is supported for slideable movement between the front mounting plate 365 and the parallel rear mounting plate 369. A slide rod or supporting rod 385 is pin connected to the plunger 384 as indicated at 386 (FIG. 57), and the rod 385 is slideable through a vertical passage 387 through the crosshead 360. A washer 389 is pin connected as indicated at 390 to the lower end of the rod 385 to limit upward movement of the plunger 384 relative to the crosshead 360. When the upward movement of the connecting bar 361 is stopped by the frame members 364 and after the clearance distance between the crosshead 360 and the plunger 384 has been taken up (allowing the levers 371 to pivot prior to crimping) the lower end of the plunger 384 is engaged by the crosshead 360 and forced upwardly from the position shown in FIG. 55 of the drawings to the position illustrated in FIGS. 56 and 57. The upper surface of the plunger 384 is slotted as indicated at 391 to accommodate three anvil plates 392. The anvil plates 392 are of the form best illustrated in FIG. 53 of the drawings. Each plate 392 is generally rectangular, but includes diagonally cut upper corners 393. The center portion of the top of each anvil plate is provided with a slightly upwardly extending anvil 394 (see FIGS. 52 and 53) which are substantially flush with the bases of the notches in the mounting plates 365 and 369. The anvil plates 392 are supported by pivot pins 372 and 395 which extend through the mounting plates 365 and 369 for support thereby. Each anvil plate 392 is also provided with a central vertical slot 396 designed to slidably accommodate a pivot pin 397.

Four pairs of crimping jaws 399 are pivotally supported in spaced parallel relation upon each pivot shaft 395 and 372. As is indicated in FIG. 54, the jaws 399 are provided with hook-shaped ends 400 which are designed to engage the side walls 257 of a clip 259 and to flex the clip side walls inwardly and downwardly toward the position indicated in FIG. 37d. Links 401 are pivotally connected to the jaws 399 of each pair by means of an elongated pivot 402 which extends through the outer ends of each jaw 399 and through the upper ends of the corresponding links 401. The lower ends of the links 401 are notched as indicated at 403 so as to dove-tail together in such a manner that the links 401 may be on the same plane. The pivot shaft 397 extends through the lower ends of the links 401 and through the slots 396. The pivot shaft 397 also extends through slots 404 in the end plates 365 and 369, and through the upper end of the plunger 384. Thus, the pivot shaft 397 pivotally connects the links 401 to the plunger 384, and upper movement of the plunger causes the links 401 to pivot the jaws 399.

Second sets of jaws are pivotally supported between the first crimping jaws 399, the second crimping jaws being indicated by the numeral 405. As indicated in FIG. 53, the jaws 405 are pivotally supported on pivot shafts 406 which are outwardly of the periphery of the anvil plates 392. The pivot shafts 406 extend through the jaws 399 and also through the jaws 405 to pivotally connect the first set of jaws with the second. The pivot shaft 406 forms the pivotal support for the jaws 405. As will be noted, each jaw 405 is arcuately slotted as indicated at 407, the center of arcuation being the axis of

the corresponding pivot shaft 406. The lower ends of the jaws 405 are notched as indicated at 409 so that the ends will overlap while the jaws 405 are maintained on a common plane. A pivot shaft 410 pivotally connects the lower ends of the jaws 405 which shaft is slidable in a vertical slot 411 in each anvil plate 392.

The jaws 405 are provided with rounded hook ends 421 which are designed to engage the side walls 257 of the clip 259, and to assist in bending the sides of the clip inwardly. The jaws 405 are pivotal about the pivot shaft 410 and are swung upwardly by arcuate movement of the pivot shafts 406. The motion of the jaws 405 is generally inward and downward. As the crimping action progresses the jaws 399 take over completely from the jaws 405. A somewhat corrugated form is imparted to the seal in crimping due to the crimping jaws 399 being spaced between the anvil plates 392 and force a portion of the seal below the plane of the anvils to increase the gripping power of the seal.

The jaws 405 serve the purpose of engaging the clip sides 257 prior to engagement of the jaws 399 with the clip sides to facilitate the inward bending and folding of the clip sides, so that the jaws 399 may complete the clipping operation. As the jaws 399 and 405 are pivoted toward each other by the links 401, the rounded ends of the jaws 405 engage the upper edges of the clip 259, bending the sides inwardly and then downwardly, assisting the jaws 399 in crimping the portions of the clip between the anvil plates.

FLOW DIAGRAM

FIG. 60 shows the general flow diagram, but eliminates numerous safety valves which prevent malfunction in the event each movement is not properly completed in series. There are numerous such valves actually used in the circuit to prevent injury to the machine or to the operators during the cycling of the apparatus. In the diagram, the letter "P" has been used to indicate a pressure supply. The pressure supplied to various elements is not usually identical, as the compression cylinder, for example, is operated at higher fluid pressure than various other cylinders.

The cycle is started by actuation of a solenoid valve 415 which is normally controlled automatically when a stack of bags is delivered into the accumulator. For the purpose of simplification, the valve 415 may be considered manually actuated by closure of a circuit to the coil 416 of the valve 415, opening this valve to direct fluid from P through valve 415 to a valve 417. The normally closed valve 417 is opened by fluid flowing through a hopper limit valve 419 physically opened by the hopper E when the hopper is in vertical stack receiving position. When open, fluid under pressure may flow from pressure P and valve 419 through a conduit 420 to a valve 421 and continues through the valve 421 and a conduit 422 to the upper end of valve 417, opening this valve.

The valve 421 is a button operated valve which is actuated by contact with a stack of bags in the hopper E, and prevents the opening of the valve 417 if the hopper is already filled. When empty, the fluid may flow through this valve 421 to open valve 417. With the valve 417 open, fluid may flow through the conduit 423 to move the valve 424 controlling the cylinder plunger 11. When the valve 424 is moved to the right pressure P

flows through the valve 424 to the left side of the cylinder 11, advancing the plunger and forcing the stack of bags into the hopper E. When the stack C is in the hopper, the button valve 421 is moved to its right hand position, closing the valve 417.

Reversal of the position of the valve 421 acts to initiate pivoting of the hopper E. Fluid under pressure flows from P through hopper limit valve 419 through conduit 420 to valve 421, and through the line 425 to a valve 426. Valve 426 is a limit valve which has been opened by the horizontal transfer mechanism in its retracted position. Fluid flows through valve 426 and line 427 to the lower end of the valve 429, changing the position thereof. Pressure P then flows through valve 429 to the lower end of the hopper cylinder 80, pivoting the hopper. Simultaneously fluid is directed through line 430 to the valve 424, directing fluid through this valve to the transfer cylinder 11, returning this plunger to starting position.

Pressure also flows through line 428 to the seal die cylinder 265, advancing the seal strip and forming and cutting a seal. As the hopper is pivoted, pressure is also applied to the precompression cylinder 86 through conduit 428, holding the stack firmly in the hopper. A restriction 431 is in the line to the hopper cylinder insures the clamping of the stack before the hopper is tilted to any great extent. As the hopper tilts, the valve 419 changes its position.

30 Tilting the hopper E continues until the hopper strikes limit valve 432, opening this valve. Fluid may then flow from P through valve 419, line 433 limit valve 432 and line 434 to valve 435, changing the position thereof. Pressure P then flows through valve 435 to the left end of horizontal transfer cylinder 115 moving the stack of bags to the compression position. The limit valve 436 is opened when the transfer cylinder is in stack compression position. The opening of valve 432

35 also acts to change the position of a valve 437 to open this valve. Pressure P flows through valve 437, through line 439 and valve 436, and then through line 440 to the left end of valve 441. The 441 is moved to the right, and fluid under pressure flows through line 442 to the compression cylinder 124, compressing the stack of bags. When the limit valves are opened by movement 40 of the compression cylinder, pressure P flows through limit valve 444 and line 445. Pressure in line 445 acts to move the button valve 421 to starting position, and also

45 to change the position of valve 429, to return the hopper actuating cylinder 80 to starting position. The changing of the position of valve 429 also directs fluid to the bottom of the precompression cylinder 86, returning the seal die 265 to starting position. Fluid also flows through line 446 to "one shot" timing valve 447, opening this valve momentarily. When open, fluid flows from pressure P through valve 447 and line 449 to the lower end of valve 450 changing the position of

50 this valve. Before actuating valve 450, fluid is directed through valve 450 to the top of chain cylinder 451, holding the chains retracted. Upon actuation of valve 450 pressure is directed through valve 450 and line 452 to the bottom of cylinder 165, moving the chains 155 about the compressed stack of bags.

55 When the chains are fully advanced, the limit valve 453 is physically actuated, changing the position

thereof. Fluid then flows from pressure P through valve 453 and line 454 to the left end of valve 455, changing the position thereof. Fluid then flows through line 456 to the right end of strap advance cylinder 241, advancing the straps 177 into the strap clamps 167 at the ends of the chains. The line 456 also leads to the top of a valve 457, changing the position thereof. Fluid then flows from P through valve 457 and line 459 to the left end of clip advancing carriage 330, advancing the strap seal into sealing position. Fluid also flows through line 460 to the upper end of valve 450 changing the position thereof. Fluid also flows through a restriction 458 from line 460 to the right side of valve 455, shifting the position thereof as soon as the chains start to retract and close valve 453. Fluid P then flows through valve 450 and line 451 to the upper end of cylinder 165, retracting the chains 155.

When the chains are fully retracted, a limit valve 461 is physically actuated, directing fluid from pressure P through valve 461 and line 462 to the right end of valve 463, changing the position thereof. Pressure flows from P through valve 463, and line 464 to the right end of crimping cylinder 355 advancing the crimper element and crimping the seal about the straps. When the crimping device is fully advanced, a limit valve 465 is physically moved. Fluid then flows from P through valve 465 and line 466 to the left hand end of valve 463, directing fluid from P through line 467 to crimper cylinder 355, retracting the crimper.

At the time the position of the valve was changed to actuate the hopper tilting cylinder fluid under pressure is also directed through line 470 to the right end of a valve 471 controlling the flow of fluid to the cutter cylinder 229 and strap release cylinder 247, changing the position thereof. Fluid then flows through the lines 472 and 473 to the cutter cylinder 229 and strap release cylinder 247, moving them to one extreme position. This pressure is cut off when the valve 426 is released by motion of cylinder 115. When the crimping cylinder 355 is fully advanced, fluid also flows through limit valve 465 through lines 466 and 469 to the left end of valve 471, changing the position thereof. Fluid then flows from P through valve 471 and line 474 to the right end of the cutter cylinder 229, moving the piston, therein cutting the strap. Fluid also flows through line 474 to a limit valve 475 which is closed when the crimping unit is partially retracted. This directs fluid through line 479 to the lower end of a valve 480, opening this valve. Fluid then flows from P through line 481 to strap release cylinder 247, releasing the sealed straps. Fluid is also directed to the right end of valve 441, causing fluid to flow through valve 441 and line 482 to the lower end of compression cylinder 124, retracting the pressure plate connected thereto. As the pressure plate reaches retracted position, a limit valve 483 is actuated, directing fluid through valve 437, line 484, limit valve 483 and lines 485 and 486 to the valve 435, changing the position thereof. This action directs fluid to the right end of transfer cylinder 115, moving the transfer mechanism back to starting position. Fluid also flows through the limit valve 483 through lines 485 and 487 to the op of valve 480, closing this valve.

The cycle is then completed and is in readiness for the next cycle. As soon as the switch 415 is actuated, the new cycle starts.

From the foregoing description it will be seen that the stack of bags is inserted into the hopper, the hopper tilted, the stack transferred to compression position, and compressed. The straps are drawn into position encircling the bale, and clipped together. The strapped bale is transferred to discharge position and discharged. This entire operation is completely automatic, one movement initiating the next automatically.

In accordance with the Patent Statutes, I have described the principals of construction and operation of my baling apparatus; and while I have endeavored to set forth the best embodiment thereof, I desire to have it understood that obvious changes may be made within the scope of the following claims without departing from the spirit of my invention.

I claim:

1. A baling apparatus for applying a flexible strap about a bale including:
a platen,
wall structures at opposite sides of said platen,
a compression plate movable toward and away from said wall structure and forming a baling chamber when engaged with said wall structures,
a chain track extending continuously through said wall structures, said compression plate, and said platen,
a continuous slot communicating with said chain track and the inner surfaces of said baling chamber,
a chain slideable in said chain track,
a strap clamp adapted to engage the strap on one end of said chain overlying said slot,
means engaging said chain to advance said one end of said chain through said track and about a bale enclosed in said baling chamber,
means engaging said chain to retract the chain, pulling said strap about the bale in said baling chamber.
2. The structure of claim 1 and in which said slot is laterally offset from said chain track.
3. The structure of claim 1 and including strap advancing means engageable with said strap to move the strap into engagement with said strap clamp.
4. The structure of claim 1 and in which the ends of said track overlap.
5. The structure of claim 1 and in which one of said wall structures includes a movably supported section which is advanceable and retractable relative to the remainder of said one wall structure, said movably supported section including a first chain track section in which the chain is at all times engaged, and a second chain track section in overlapping relation to said first chain track section, said first chain track section being aligned with the chain track in the remainder of said one wall structure, and said second track section aligning with the chain track in said platen when said movably supported section is fully advanced.
6. The structure of claim 5 and in which said movably supported section is moved by movement of said chain.
7. The structure of claim 5 and including lock means on said movable section engageable with said chain to prevent relative movement between said chain and said movable section when said movable section is out of fully advanced position.

8. The structure of claim 5 and including securing means supported adjacent to said movable section and securing overlapping portions of said strap together when said movable section is in retracted position.

9. The structure of claim 5 and including strap cutting means on said one wall structure adjacent to said movable section.

10. The structure of claim 5 and including strap advancing means on said one wall structure adapted to be engageable with the end of said strap to advance said strap into said movable section when the same is in fully advanced position for engagement with said clamp.

11. An apparatus operable upon a length of flexible strap having a free end and a supply end for forming a loop of strap about an object comprising:

a frame including a chain track extending entirely around the space within said frame,

a chain slideable in said track having a free end normally in a starting position,

said frame including a slot communicating with said track and communicating with the interior of said frame,

a strap clamp supported at the free end of said chain and overlying said slot,

means adapted to support the free end of the tape in the path of movement of said strap clamp after said free end of said chain has traveled about said track and,

means for driving the free end of said chain and said strap clamp about said track, and for reversing the movement of said free end of said chain and said strap clamp and adapted to draw the strap about

said object upon movement of said free end of said chain to said starting position.

12. The structure of claim 11 and in which said strap clamp includes a fixed jaw and a movable jaw between which said free end of said strap is adapted to engage.

13. The structure of claim 11 and in which the clamp comprises a bifurcated end including a trapezoidal slot with the narrow end of the slot at the end of the clamp and into which said strap is adapted to extend, and a wedge shaped jaw slideable along one side of said slot.

14. The structure of claim 13 and in which the other side of the slot and the adjoining side of the jaw are provided with toothed surfaces.

15. The structure of claim 11 in which said means for driving said chain includes a sprocket, and means for selectively rotating said sprocket in either direction.

16. The structure of claim 15 and in which said means for driving said chain includes a gear mounted for rotation with said sprocket, and a gear rack engaging said gear for rotating the same.

17. The structure of claim 16 and including a piston and cylinder device engaged with said rack to actuate the same.

18. The structure of claim 11 and in which said track includes overlapping end portions.

19. The structure of claim 18 and in which the end of the track at which said means adapted to support the free end of the tape is located is inwardly of the end of the track to which said strap clamp is retracted when in said starting position.

20. The structure of claim 18 and including means adapted for securing the overlapping ends of the tape together.
